(57) **CLAIM**

The ornamental design for a toy gun, as shown and described.

DESCRIPTION

FIG. 1 is a first perspective view of a toy gun showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged partial view taken from FIG. 1;

FIG. 10 is an enlarged partial view taken from FIG. 2;

FIG. 11 is an enlarged partial view taken from FIG. 2; and,

FIG. 12 is an enlarged partial view taken from FIG. 2.

The dash-dot broken lines represent the boundaries of the enlarged partial view of FIGS. 9-12. All other broken lines represent portions of the toy gun that form no part of the claimed design. None of the broken lines form a part of the claim.

1 Claim, 12 Drawing Sheets
